PAIR OF SAFETY GOGGLES

William J. Black, Clearfield, Pa., assignor to The Burdett Oxygen Company of Cleveland, Inc., Cleveland, Ohio, a corporation of Ohio

Application March 14, 1957, Serial No. 45,261

Term of patent 3½ years

(Cl. D57—1)

Fig. 1

Fig. 2

Fig. 3

Fig. 4

Fig. 5

Fig. 1 is a front elevation of a pair of safety goggles embodying my new design.

Fig. 2 is a top plan view of the same.

Fig. 3 is a bottom plan view of the same.

Fig. 4 is a side elevation of the same as viewed from the right side of Fig. 1.

Fig. 5 is a side elevation of the same as viewed from the left side of Fig. 1.

I claim:

The ornamental design for a pair of safety goggles, substantially as shown.
